(57) **CLAIM**

The ornamental design for a tank winglet, as shown and described.

DESCRIPTION

This application contains related subject matter by a common inventor with:

U.S. application Ser. No. 29/773,302, titled “Projectile-Shaped Trailer Air Tank,” filed by Gerald Pearson, et al., on Mar. 9, 2021;

U.S. application Ser. No. 29/718,772, titled “Tank Trailer Airfoil,” filed by Gerald Pearson, et al., on Dec. 27, 2019; and,

U.S. application Ser. No. 17/302,366, titled “Tank Trailer Airfoil Structures and Methods,” filed by Gerald Pearson, et al., on Apr. 30, 2021.

FIG. 1 is a side elevation view of a tank winglet showing the new design in the context of an exemplary trailer;

FIG. 2 is a lower-right perspective view of the tank winglet of FIG. 1;

FIG. 3 is a front elevation view of the tank winglet of FIG. 1;

FIG. 4 is a rear elevation view of the tank winglet of FIG. 1;

FIG. 5 is a left elevation view of the tank winglet of FIG. 1;

FIG. 6 is a right elevation view of the tank winglet of FIG. 1;

FIG. 7 is a bottom plan view of the tank winglet of FIG. 1; and,

FIG. 8 is a top plan view of the tank winglet of FIG. 1.

The broken lines in the drawings illustrate portions of the tank winglet and environmental structure of a tank trailer that form no part of the claimed design.
